US0D1026696S

(12) **United States Design Patent** (10) Patent No.: **US D1,026,696 S**
(45) Date of Patent: ** May 14, 2024

(54) **WEIGHT DETECTION SENSOR**

(71) Applicant: **HOME CARE AITECH, INC.**, Newark, DE (US)

(72) Inventor: **Serdar Şişman**, Istanbul (TR)

(**) Term: **15 Years**

(21) Appl. No.: **29/909,841**

(22) Filed: **Aug. 11, 2023**

Related U.S. Application Data

(62) Division of application No. 35/515,249, filed on Jun. 23, 2022 (U.S. filing date under 35 U.S.C. 384), and having an international filing date of Jun. 23, 2022.

(51) **LOC (14) Cl. 10-05**

(52) **U.S. Cl.**

USPC **D10/106.9**

(58) **Field of Classification Search**

USPC D10/70, 106.6, 106.9, 106.91, 106.92, D10/106.93, 106.94

CPC G08B 13/08; G08B 21/18; G08B 29/046; G01R 33/0206; G01R 33/0286; G06K 19/07758

See application file for complete search history.
